CORROSION PREVENTING DEVICE

Emert J. Lattner, Cedar Rapids, Iowa

Application December 18, 1940, Serial No. 370,637

2 Claims. (Cl. 204—197)

This invention relates to devices for minimizing or preventing the deposition of scale, corrosion and the like on boilers, and has particular relation to means for indicating when such a device has lost its effectiveness, and for replacing the active element of such a device.

It is well known that the action of boilers causes the precipitation of calcium, lime and other materials from the water. Also chemical and electrolytic action may be set up which corrodes the exposed surfaces. It is perhaps not so well known that, if a cartridge or the like of dissimilar materials is placed within the boiler or in the hydraulic system in such a manner that water in the boiler passes around or through the cartridge, the deposition of scale and the like and the destructive effects of electrolytic and chemical action on the walls and other parts of the boiler are minimized or prevented.

It is obvious, however, that in devices of this character one of the dissimilar materials or electrodes, which would of course be the metal higher in the electro-chemical scale, will gradually become consumed—that is, the particles of one of the electrodes will combine chemically with the water or other fluid of the boiler, and the electrode will be gradually eaten away, thus destroying the effectiveness of the device.

It is one of the main objects of my invention to provide a device in which the active electrode may be readily replaced by a new element after its effectiveness has become destroyed.

Still another object of my invention is to provide means for signalling that the active electrode is no longer effective so that it may be replaced.

Still another object of my invention is to provide means for withdrawing the remaining parts of the active electrode and for replacing and resetting the moving parts of the signalling means.

Other and further features and objects of the invention will be more apparent to those skilled in the art upon a consideration of the accompanying drawing and following specification, wherein are disclosed several embodiments of the invention, with the understanding, however, that such changes may be made therein as fall within the scope of the appended claims, without departing from the spirit of the invention.

In said drawing:

Figure 1 is a view, partly in elevation and partly in section, of a device constructed according to one embodiment of my invention.

Figure 2 is a view in side elevation of a boiler

to which a device such as shown in Figure 1 has been connected, and

Figure 3 is a view, partly in section and partly in elevation, of a modified form of an electrode and valve for the device shown in Figure 1.

Referring now to the drawing:

In practicing my invention I preferably employ a cylindrical cartridge such as that indicated generally at 10 and including an outer cylinder or electrode 11 and an inner electrode 12. The outer cylinder and the inner electrode are of dissimilar materials and copper is preferably employed for the outer cylinder and zinc or the like for the inner rod or pipe 12.

Of course any other suitable dissimilar metals may be employed which are sufficiently far apart on the electro-chemical scale to produce an electric current in the boiler water. Furthermore, forms other than cylindrical may be employed for the electrodes.

These cylinders are preferably joined by means of an electrical conductor such as the cap 13. They may also be joined at the lower end as by means of the valve member 14 which, in this instance, is loosely received within the cylinder.

Openings are provided at the top and bottom or at the sides of the cylinder, as indicated at 28 and 16 and 17, to permit water to flow through the cylinder.

Now this cylinder, as so constructed, may be inserted within a boiler through intake or outlet openings in the boiler or, in the case of large boilers, through hand-holes or the like, but I preferably place the device outside of the boiler and connect it in such a manner that convection currents or thermo siphon action of the water into and out of the boiler causes circulation of the boiler water through the cartridge. A typical connection is illustrated in Figure 2 in conjunction with Figure 1.

The return or inlet pipe leading to the boiler 21 is indicated at 22 and the outlet pipe or main riser at 23. I preferably enclose the cartridge in a cylindrical shell 24, and water from the outlet pipe 23 passes, by reason of thermo siphon action, through pipe 26 and valve 27 into the chamber within the shell 24, in through the openings 28 of the outer shell 11, down through the space between the inner pipe 12 and the outer cylinder 11, and down through the openings 17 in the valve body 14. The water then passes through the opening in the valve seat 29 and down through the conduit 31 through valve 32 and into the intake or return pipe 22. A flange 55 is preferably provided on the inner wall of the

cylinder 24 at 25 to constitute a baffle to cause the water to flow between the cylinders.

The outer shell 11 is of a size such as will provide a fit over an enlarged portion or flange 33 extending below the cap 13, and the inner electrode 12 is threaded at the upper end, as indicated at 34, and is received in a threaded opening in the cap 13. The lower end of the electrode 12 is threaded into a similar recess, as at 41, in the valve body 14. The valve body 14 is provided with an elongated stem, indicated at 36, for guiding the valve body as it drops downwardly when released by disintegration of the electrode 12.

The cap 13 is provided with an extension of the recess in which the electrode is received, which extension is indicated at 37, and a similar extension of the recess in the valve body 14 is provided at 38. A rod of any suitable material such as copper or steel or the like, indicated at 39, passes through the inner electrode 12 and its ends are received within the recesses 37 and 38. Washers 41 having a loose fit on the rod 39 are provided at the opposite ends of the pipe electrode 12 and secured in place in the cap 13 and valve body 14 when the electrode is screwed into place. The rod has an enlarged button-like end 42 at its lower end and is provided with a nut 43 at the upper end so that while the valve body may drop into seating engagement with the valve seat 29 by reason of disintegration of the electrode 12, it may be removed by unscrewing the cap 13 and raising the cap directly vertically above the cylinder 24. The enlarged end of the rod and the nut 43 tie the cap, the valve, and the electrode together so they may be removed as a unit.

A blow-out valve is provided at 44 so that any accumulation of material in the bottom of the cylinder may be forced out by opening the valve.

When the apparatus is in use, an electric current flows from one electrode to the other, and the negative electrode, in this case the electrode 12, will be gradually disintegrated by chemical action. When disintegration has progressed to the point where the electrode is entirely eaten away, the valve 14 will drop and the valve face at 14a will rest on the seat 29 to close the conduit 31. As long as the electrode 12 is whole and the boiler is in operation, there is a flow of water through the cylinder 24 and the cylinder is warm to the touch, but when the electrode becomes eaten through, thus destroying its effectiveness, it can no longer hold up the valve 14 and the valve will drop to close the conduit 31. When the conduit 31 is closed the cylinder cools off because it is no longer being heated by the boiler water. Thus if the boiler is operating and the cylinder is not hot to the touch, it is an indication that the electrode 12 has been eaten away and should be replaced.

In order to replace the electrode 12, the cap 13 may be unscrewed to remove the assembly consisting of the cap 13, the electrode 11, the remaining portions of the electrode 12, the rod 39, and the valve 14. The electrode 12 may be replaced with a new electrode and the apparatus

reassembled to become again effective. At the same time the electrode 11 may be cleaned and replaced if necessary.

A modified form of the invention is illustrated in Figure 3, in which a chain 46 of copper, brass or the like is substituted for the rod 39. This form of the invention does not require the extensions of the bores within the cap and valve, which are used in the form of the invention ill-

10 10 illustrated in Figure 1, for the reason that the excess chain may normally double up to permit the valve 14 to drop into seating engagement with the valve seat 29 when the negative electrode is eaten away.

15 15 Although I have described a specific embodiment of my invention, it is apparent that modifications may be made by those skilled in the art. For instance, a temperature indicator, or any other device suitable for indicating the cessation 20 20 of flow of water through the cylinder may be employed as a signalling device instead of relying on the detection of temperature differences by touching the cylinder. These and other modifications are within the scope of the invention 25 25 and may be made without departing from the spirit and scope of my invention as set forth in the appended claims.

I claim as my invention:

1. In a device of the character described, a 30 30 casing having inlet and outlet ports, a cap removably mounted in the top thereof, a pair of electrically dissimilar metal electrodes concentrically arranged and suspended from said cap, the outer of said electrodes being hollow and of 35 copper, and the inner being of zinc, a valve supported by said zinc electrode and disposed vertically over the said outlet port whereby disintegration of the said zinc electrode due to electrolytic action between said electrodes will drop 40 40 said valve member to cover said outlet port, and means extending through the said electrodes for loosely connecting said cap member and said valve member, whereby said valve member may be lifted out of the casing by the connecting means.

45 45 2. In combination with a boiler, means for treating the boiler water including a by-pass conduit through which the boiler water passes by reason of thermosyphon action, a chamber in the by-pass conduit and a water treatment device in the chamber, said water treatment device consisting of two concentrically arranged electrodes, the outer electrode being composed of copper, while the inner electrode is composed of zinc, the electrodes being connected to cause electrolytic action therebetween, and valve means normally engaged by the inner electrode of the water treatment device and adapted, upon release by reason of disintegration of the inner electrode, to close the conduit, to stop circulation of water through the by-pass, to cause lowering of the water temperature in the device to thus signal that the device has lost its effectiveness.
